UNITED STATES PATENT OFFICE.

SAM B. WHITE, OF PORTSMOUTH, OHIO.

AUTOMATIC COUPLING.

1,168,692.

Patented Jan. 18, 1916.

Specification of Letters Patent. Application filed June 10, 1915. Serial No. 33,363.

To all whom it may concern:

Be it known that I, SAM B. WHITE, a citizen of the United States, residing at Portsmouth, in the county of Scioto and State of Ohio, have invented a new and useful Automatic Coupling, of which the following is a specification.

The present invention appertains to train pipe couplings, and aims to provide novel and improved means for automatically coupling together, the air, steam or other pipe sections of a pair of railroad cars, when the cars are coupled together, so that it is not necessary for the brakeman to manually couple the pipe sections together as usual.

One of the specific objects of the invention is the provision of unique means for mounting the tubular members which are employed for coupling the pipe sections together, whereby said tubular members may swing and slide to be properly coupled together under various conditions, as when rounding a curve, or when one tubular member is out of alinement with the other for any reason whatever.

Another specific object of the invention is the provision of novel means carried by the tubular members for bringing them into alinement and abutment.

It is also within the scope of the invention to provide an appliance of the nature indicated which is quite simple and inexpensive in construction, which may be readily installed upon railway cars and coaches, and which will serve its office in a practical and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a bottom view of the improved coupling at the initial moment of coupling. Fig. 2 is an enlarged longitudinal

section thereof taken on the line 2—2 of Fig. 1. Fig. 3 is an enlarged end view of one of the coupling members. Fig. 4 is a longitudinal section of the coupling member taken on the line 4—4 of Fig. 3. Fig. 5 is a perspective view of one of the slidable plates. Fig. 6 is a fragmental perspective view of one of the tubular members. Fig. 7 is a perspective view of one of the spherical members.

In carrying out the invention, hangers or supporting members 1 are attached to the end sills S of the railway cars, the hangers 1 being located at the adjacent ends of the cars, and the hangers 1 are provided with spherical pockets or openings 2 therein within which are journaled for rotation in various directions, spherical members 3. Plates 4 and 5 are attached to the inner and outer sides of the hangers 1 for holding the spherical members 3 within the hangers, and said plates 4 and 5 are provided with openings 6 exposing said spherical members. Said spherical members are provided with square or non-circular bores 7.

Tubular members 8 are slidable through the bores 7 and are of square or non-circular cross section where they slide through the bores 7 to allow the members 8 to slide relative to the members 3, but to prevent said members 8 from rotating with respect to said members 3. To the remote ends of the tubular members 8 are attached the hose sections 9 which are connected to the pipe sections (not shown) carried by the cars. The present appliance may be employed for connecting the train or air pipe sections, the steam pipe sections, or other pipe sections carried by the cars.

Spiral springs 10 have their larger ends bearing against the outer plates 5 of the hangers 1, and surround the tubular members 8, the smaller ends of the springs 10 bearing against collars 11 carried by the tubular members 8 near their outer or adjacent ends. These springs 10 tend to project the tubular members 8 outwardly, and allow said members to yield when they abut against one another.

Collars 12 are clamped upon the tubular members 8 behind the hangers 1, by means

of set screws 13, and limit the outward movement of the tubular members 8 under the influence of the springs 10.

Slidable plates 14 are carried by the inner plates 4 of the hangers 1, and are provided with rectangular or non-circular openings 15 through which the tubular members extend, whereby said tubular members are permitted to oscillate vertically and horizontally to a limited extent, but are prevented from rotating about their axes. The plates 14 are guided for vertical sliding movement by guides 16 carried by the plates 4, and this prevents the plates 14 from rotating.

15 The collars 12 bear against the plates 14.

The adjacent or meeting ends of the tubular members 8 are cut obliquely, as at 17, and are provided with gaskets 18, or with ground bearing surfaces, whereby when the members 8 abut, a tight joint will be provided therebetween.

As a means for properly guiding the members 8 into alinement and abutment, the outer end of each member 8 is provided 25 with an outstanding lug 19 adjacent the outer end of the oblique end face 17, as clearly seen by reference to Fig. 4. The end face 17 of the tubular member 8 is disposed in a vertical plane, whereby the lug 19 is arranged at one side of the said member, while the other side of the member 8 carries a scoop-shaped guiding wing 20. This wing has an arcuate basal portion 21 soldered or otherwise secured to the respective side of the member 8 at the inner end of the end face 17, and the body portion 22 of the wing 20 projects from the basal portion 21. The body portion 22 of the wing and end face 17 diverge from one another, as seen 40 in Fig. 4, and the body portion 22 of the wing is curved between its upper and lower edges, the portion 22 increasing in width from its basal to its free end. The portion 22 has upper and lower inturned flanges 23, and the portion 22 is provided with an out-struck portion 24 adjacent the end face 17 of the member 8 for receiving the lug 19 of the other coupling member 8.

The guide lugs 19 and wings 20 of the two 50 tubular members 8 are located at opposite sides, due to the reversal of the two coupling members, as seen in Fig. 1, and each wing 20 is arranged to receive the lug 19 of the other tubular member 8 when the parts 55 are coupled together. Supposing the cars to be separated or uncoupled, the members 8 will be projected by the springs 10 until the collars 12 bear against the plates 14, which limits the outward movement of the members 8. Then, when the two cars are 60 coupled together, the tubular members 8 will be moved together, and the lugs 19 will be received or caught by the opposite wings 20, in order that the members 8 will properly 65 abut against one another to provide a tight

joint therebetween. Should the members 8 be spaced at different vertical planes, the lugs 19 in engaging the upper and lower inclined or converging flanges 23 of the wings 20, will bring the members 8 into the same vertical plane, and the lugs 19 in bearing against and moving along the body portions 22 of the wings, will move the members 8 sidewise into alinement. The lugs 19 are finally received in the outstruck portions 24 of the wings 20, which causes the members 8 to aline and abut properly, the inclined faces of the two tubular members bearing snugly against one another. When the members 8 are brought together, they will be moved against the tensions of the springs 10, whereby the said springs serve to tightly hold the members 8 together, and due to the fact that the members 8 are slidable through the spherical members 3, they may slide and swing properly when they are brought together. The members 8 may also swing relative to the hangers 1 due to the movements of the cars relative to one another, but there is no liability of the members turning or rotating about their axes, which would be liable to displace the adjacent ends of the members 8. When the cars are uncoupled and separated, the members 8 will leave one another.

The present appliance is operable for automatically connecting the pipe sections when the cars are coupled together, and without the intervention of the brakeman, which saves time and trouble.

The present coupling may not only be used upon railroad cars, but may also be used for other purposes, for connecting the pipes or hose sections with one another when they are moved toward each other.

Having thus described the invention, what is claimed as new is:

1. In an appliance of the character described, a pair of supporting members, spherical members carried thereby for oscillations in various directions, tubular members of non-circular cross section slidable through said spherical members, the adjacent ends of the tubular members having co-operating guiding means for guiding the tubular members into abutment, means for yieldably projecting the tubular members, movable plates carried by the supporting members and having non-circular openings through which the tubular members extend, means for preventing the rotation of the said plates, and means for limiting the movement of the tubular members.

2. In a coupling, a pair of tubular members having oblique end faces adapted to abut, each tubular member having an outstanding lug at the outer end of its face, a guiding wing having its basal portion attached to each tubular member at the inner end of its face, the wing having a curved

body portion increasing in width from its basal to its free end, said body portion diverging from said face and having inturned flanges at its edges, and said body portion of the wing having an outstruck portion adjacent said face for receiving the lug of the other tubular member.

In testimony that I claim the foregoing as my own, I have hereto affixed my signature in the presence of two witnesses.

SAM B. WHITE.
